UNITED STATES PATENT OFFICE.

RICHARD W. AMOS, OF PATERSON, NEW JERSEY, ASSIGNOR TO NATIONAL PURIFICATION COMPANY, OF NEW YORK, N. Y., A CORPORATION.

DRYING AND CONDENSING APPARATUS.

965,058.

Specification of Letters Patent. Patented July 19, 1910.

Application filed October 3, 1908. Serial No. 456,039.

To all whom it may concern:

Be it known that I, RICHARD W. AMOS, a citizen of the United States, and a resident of Paterson, in the county of Passaic and State of New Jersey, have invented certain new and useful Improvements in Drying and Condensing Apparatus, of which the following is a specification.

This invention relates to drying and condensing apparatus.

By the use of my invention, sludge obtained from sewage water and also vegetable and other organic substances may be thoroughly dried and said sludge and other substances converted into a condition suitable for burning as a fuel. Furthermore, valuable chemical products given off by said substances will be recovered, condensed and separated from each other, as will herein-
20 after be more particularly specified.

My preferred form of apparatus comprises a tank or cylinder for containing the material to be dried, a furnace and flue suitably located for effectively subjecting the tank or cylinder externally to heat, means for stirring or disturbing the material within the tank in order to obtain a thorough drying thereof, and condensing apparatus in proper communication with the tank or cylinder for receiving, condensing and separating the valuable chemical vapors evolved in the drying operation.

Other important features connected with the invention are clearly explained in the subsequent detailed description.

In the accompany drawings, forming part of the specification, Figure 1 is a vertical sectional view of the drier constituting a prominent feature of the present invention, the plane of section being to one side of the tank or cylinder and part of the latter being broken away to show more clearly the agitating or stirring means. Fig. 2 is a vertical transverse sectional view of the construction indicated in Fig. 1, the plane of section being immediately forward of the furnace bridge. Fig. 3 is a detail view illustrating the mergence of the upper longitudinally disposed flues immediately contiguous to the discharge outlet or stack. Fig. 4 is a detail view illustrating the vapor receiving, condensing and separating feature of the apparatus. Fig. 5 is a detail view of one of the agitating or stirring arms within the tank or cylinder.

Similar reference characters designate corresponding parts throughout the several views.

In the preferred form of my invention illustrated in the accompanying drawings, 60 the frame A is represented as of masonry having usual lower forwardly-located furnace A', conditioned in a manner which may be readily understood. Such frame is preferably so formed that when the tank or 65 cylinder B is suitably supported thereon, a lower rearwardly leading flue B', an uptake B² and two forwardly leading flues B³, B³ will be provided between such tank and the frame. The lower rearwardly leading flue 70 B' together with the furnace A' will preferably have a capacity ample to bathe the lower half of said tank B. The uptake B², which is preferably located at the rear of the tank or cylinder, receives the gases of 75 combustion from the flue B' and delivers the same at its upper end to the forwardly leading flues B³, B³, which extend longitudinally on opposite sides of the tank and are entirely independent of each other till 80 they merge in a short vertical passage b at the forward end of the tank, which passage delivers to the discharge or stack b'.

The tank or cylinder is preferably so situated relatively to the frame that it 85 abuts at both sides against the adjacent surfaces thereof at a point below the flues B³, B³, separating the same from the flue B' and from each other. The roofs of the flues B³, B³ are formed by the laterally 90 overhanging portions B' of the arch plate B which rests on the tank B.

Centrally located within the tank and resting at its forward end in a suitable bearing C is a shaft C which extends through 95 the rear head of the tank and rear wall of the frame a sufficient distance to permit a driving pulley e to be fixed thereon. Preferably the portion of said shaft which spans the uptake B² will be incased in a sleeve 100 C² which will provide a protecting or dead air space surrounding the same. Suitable bearings C³ are also provided for said shaft in the rear wall of the frame.

That portion of the shaft C which is 105 within the tank B carries agitating or stirring arms D which are preferably alternately arranged as indicated in Figs. 1 and 2, for the purpose of thoroughness of operation.

2
 To further promote the effectiveness of said arms, each of the same is triangular in cross-section, as shown in Fig. 5, resulting in three edges a , a' , a'' , such arms being so secured to the shaft that as the latter rotates, the edge a will be presented to the material and will cut and make a path through the same, the diverging faces a^3 acting to further separate and spread the material.

10 The tank or cylinder is provided with a charging opening B^5 preferably located at or near the center of the upper surface thereof, and a door B^6 is provided preferably at the forward end of such tank for the removal of the material.

15 From the above description, thus far, it will readily be seen that a suitable material, such as sludge, or fruit, vegetable or other appropriate matter may be introduced into the tank, the latter closed and the drying operation begun by firing the furnace. A fuel comprised of the residuum of previous drying operations in compressed form may 20 be employed for the purpose. The furnace being fired, the gases of combustion will circulate through the respective flues as hereinbefore indicated, thus subjecting a large proportion of the surface of the tank to the heat thereof, and producing a drying effect 25 upon the material contained therein. This drying of the material is rendered most thorough and complete by the action of the 30 agitating arms D in spreading and separating the material as hereinbefore described. During such drying operation, vapors containing the elements of ammonia liquors and alcohol will be driven off. For the purpose of collecting, condensing and separating 35 these vapors, I provide a pipe E communicating with the interior of the tank through its tap and preferably close to the rear end thereof. Said pipe E leads to and is connected with a condensing chamber F which 40 is provided at its lower end with a pipe f' communicating with a reservoir G. A pipe f'' connects the top of the chamber F with a condensing coil H which in turn may deliver 45 to any suitable receptacle, not shown. The ammonia liquors will readily condense in 50 the chamber F and pass to and be stored within the reservoir G while the remaining vapors will flow to the coil H where they

will be converted into alcohol and thereafter disposed of as may be desired.

Obviously, drying and condensing apparatus, such as that hereinabove described, is comparatively inexpensive to erect, operate and maintain, and its employment permits the material to be completely treated and utilized in the most economical manner.

Having now described my invention, what I claim as new and desire to secure by Letters Patent, is:

1. In apparatus of the character described, the combination with a frame embodying a furnace, a tank supported by said frame, said tank and frame work co-operating to present a lower rearwardly extending flue bathing the lower half of the tank and two upper return flues one on each side of the tank above the longitudinal center line thereof, said return flues being independent of each other for a major part of their length but terminating in a common branch, a discharge communicating with said branch, agitating means within the tank, and collecting, condensing and separating means communicating with the upper portion of said tank, as and for the purpose set forth.

2. In apparatus of the character described, the combination with a frame embodying a furnace, a tank supported by said frame, said tank and frame work co-operating to present a lower rearwardly extending flue bathing the lower half of the tank and two upper return flues one on each side of the tank above the longitudinal center line thereof, said return flues being independent of each other for a major part of their length but terminating in a common branch, a discharge communicating with said branch, a revoluble shaft within said tank, arms triangular in cross-section secured to said shaft, and collecting, condensing and separating means communicating with the upper portion of said tank, as and for the purpose set forth.

In witness whereof, I have signed my name to the foregoing specification in the presence of two subscribing witnesses.

RICHARD W. AMOS.
